DESIGN FOR A VANITY CASE

Pierre H. Pingen, Erie, Pa., assignor to Erie Plastics Company, Erie, Pa., a corporation of Pennsylvania

Application May 9, 1939, Serial No. 84,891

Term of patent 3½ years

To all whom it may concern:

Be it known that I, Pierre H. Pingen, a citizen of the United States of America, residing at Erie, in the county of Erie and State of Pennsylvania, have invented a certain new, original, and ornamental Design for a Vanity Case, of which the following is a specification, reference being had to the accompanying drawing, forming part thereof.

Fig. 1 is a top plan view of a vanity case, showing my new design.

Fig. 2 is a side elevational view, Fig. 3 is a rear view, and Fig. 4 is a front elevational view thereof.

What I claim is:

The ornamental design for a vanity case, substantially as shown.

PIERRE H. PINGEN.
